UNITED STATES PATENT OFFICE.

HOWARD T. CHINN, OF ATASCADERO, CALIFORNIA.

STOVEPIPE HOLDER.

Application filed February 6, 1926. Serial No. 86,579.

This invention aims to provide a simple but efficient means for holding a stove pipe in a chimney.

It is within the province of the disclosure 5 to improve generally and to enhance the utility of devices of that type to which the invention appertains.

With the above and other objects in view which will appear as the description 10 proceeds, the invention resides in the combination and arrangement of parts and in the details of construction hereinafter described and claimed, it being understood that changes 15 in the precise embodiment of the invention herein disclosed, may be made within the scope of what is claimed, without departing from the spirit of the invention.

In the drawings:—

Figure 1 shows in longitudinal section, a 20 device constructed in accordance with the invention, mounted in place in a chimney;

Figure 2 is a longitudinal section wherein parts are broken away;

Figure 3 is an end elevation;

Figure 4 is a perspective view showing 25 the anchor;

Fig. 5 is a fragmental elevation showing a part of the retainer.

The numeral 1 marks a chimney having a 30 flue 2 and provided with an opening 3 for the reception of a pipe.

The numeral 4 marks a pipe, one end of which is inserted into the opening 3 in the chimney 1. The numeral 5 designates, generally, an anchor, including a body 6 provided at its inner end with a foot 7, and supplied at its outer end with a shoulder 8, the foot and the shoulder being disposed about parallel to each other, and at right 40 angles to the body 6, the anchor including an arm 9 projecting from the shoulder 8 and disposed about parallel to the body 6, the arm 9 being reduced in thickness at its end, as indicated at 10.

The numeral 11 designates a retainer, in 45 the form of a finishing ring, provided with an inwardly extended flange 12 and supplied at its outer end with a notch or seat 14, of the same cross section as the arm 9 of the anchor 5. The pipe 4 is supplied with 50 an opening 15, of such size that the arm 9 of the anchor 5 may be slid readily into the said opening.

In practical operation, the arm 9 is slid 55 through the opening 15 in the pipe 4, until the shoulder 8 is located in the said open-

ing, the arm 9 lying on the outside of the pipe, and the body 6 being located partly within and partly without the pipe, as indicated in Figure 1. The body 6 is swung 60 inwardly a little, in the direction of the arrow A in Figure 1, so that when the end of the pipe 4 is stuck into the opening 3, the foot 7 on the end of the part 6 may pass through the opening 3. The arm 9 then is 65 swung down flat on the pipe 4, as shown in Figure 1. This operation brings the foot 7 upwardly into engagement with the chimney 1, within the flue 2, as shown in Figure 1, and, as a consequence, the pipe 4 cannot 70 pull out to the right in Figure 1. Furthermore, the shoulder 8 projects far enough beyond the outer surface of the pipe 4 so that the shoulder will cooperate with the outer 75 surface of the chimney 1, and limit the movement of the pipe 4 to the left in Figure 1. The finishing ring 11 is slid to the left, in Figure 1, against the chimney 1, the arm 9 of the anchor 5 being received in notch 14 of the finishing ring, the anchor 5 being 80 held against tilting at the point 8—15, and the foot 7 being maintained in such a position that it will retain the pipe 4. Since the arm 9 is reduced as at 10, it may the more readily be inserted into and received 85 within the notch 14 which is formed in the finishing ring 11.

What is claimed is:—

In a device of the class described, a stove- 90 pipe having an opening in its side wall; an anchor including a body and an arm disposed parallel to each other and a shoulder located at right angles to the body and the arm and connecting them together, the arm lying on the outside of the pipe, the body lying partly on the inside of the pipe and projecting at its outer end beyond the end of the pipe, the outer end of the body being provided with a foot disposed parallel to the shoulder, the foot and the shoulder constituting means for limiting the longitudinal sliding of the pipe in a chimney, the anchor being tiltable in the opening in the pipe, and a ring surrounding the pipe and the arm to hold the shoulder engaged in the opening whereby the shoulder will form the sole 95 means for holding the anchor against longitudinal movement with respect to the pipe.

In testimony that I claim the foregoing 100 as my own, I have hereto affixed my signature.

HOWARD T. CHINN.
